US00D748347S

(12) **United States Design Patent**
Noordzij et al.

(10) **Patent No.:** US D748,347 S
(45) **Date of Patent:** ** Jan. 26, 2016

(54) **MANDIBLE SHIELD**

(71) Applicant: **Artisent, LLC**, Simpson, PA (US)

(72) Inventors: **Duco W. Noordzij**, Roslindale, MA (US); **Kyle L. Lamson**, Chelmsford, MA (US); **David C. Rogers**, Boston, MA (US)

(73) Assignee: **Artisent, LLC**, Simpson, PA (US)

(**) Term: **15 Years**

(21) Appl. No.: **29/532,030**

(22) Filed: **Jul. 1, 2015**

Related U.S. Application Data

(63) Continuation of application No. 29/495,126, filed on Jun. 27, 2014, which is a continuation of application No. 29/479,255, filed on Jan. 14, 2014, now Pat. No. Des. 711,051.

(57) **CLAIM**

The ornamental design for a mandible shield, as shown and described.

DESCRIPTION

FIG. 1 is a front perspective view of a mandible shield showing our new design;

FIG. 2 is a front elevational view of the mandible shield shown in FIG. 1;

FIG. 3 is a rear elevational view of the mandible shield shown in FIG. 1;

FIG. 4 is a left-side elevational view of the mandible shield shown in FIG. 1;

FIG. 5 is a right-side elevational view of the mandible shield shown in FIG. 1;

FIG. 6 is a bottom plan view of the mandible shield shown in FIG. 1; and,

FIG. 7 is a top plan view of the mandible shield shown in FIG. 1.

The broken lines shown in the drawings represent portions of the mandible shield that form no part of the claimed design.

1 Claim, 7 Drawing Sheets
